UNITED STATES PATENT OFFICE.

JOHN BEN PERRY, OF OAKLAND, CALIFORNIA.

TOOL HOLDER.

1,250,645.

Specification of Letters Patent. Patented Dec. 18, 1917.

Application filed June 9, 1917. Serial No. 173,836.

To all whom it may concern:

Be it known that I, JOHN B. PERRY, a citizen of the United States, and a resident of Oakland, in the county of Alameda and State of California, have invented a new and Improved Tool-Holder, of which the following is a full, clear, and exact description.

My invention relates to a holder for tools used in connection with percussion hammers.

An object of the invention is to provide a simple and inexpensive tool which will facilitate the retaining of the tool at the hammer and also protect the hand.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a side elevation of a tool holder embodying my invention;

Fig. 2 is a longitudinal section therethrough; and

Fig. 3 is a cross section on line 3—3, Fig. 2.

In the use of percussion tools difficulty is experienced in preventing the removable tool section from being shot out, particularly in cases where the percussion tool is operated accidentally or the working tool is not in contact with the work. The object of my invention is to overcome the above defect by providing a holder.

The holder 4 is a hollow frustocone, preferably formed of sheet metal. The narrower end of the holder proper is provided with slits 5 which permit that end of the holder to expand and, therefore, makes the said end of holder yielding. These slits form fingers 6 at the narrower end which are preferably lined interiorly, near the extremities, by doubling the metal, as shown

at 7; in consequence the fingers grip better on to the tool they are to retain.

The holder is provided exteriorly with a jacket 8 of a heat-insulating material, such as fiber, for example. It has also slits 9 similar to the slits 5 to permit the spreading of the fingers previously referred to. This material protects the hand from heat to which the metallic holder may be subjected by the continuous operation of the tool. In addition the cooling of the tool is facilitated by the air passing between the slits 5 and 9.

I claim:

1. A tool holder of the class described in the shape of a hollow frustocone having slits at the narrower end for rendering said end yielding, and a jacket of heat insulating material about the cone to facilitate the handling of the holder.

2. A tool holder of the class described in the shape of a hollow frustocone having longitudinal slits at the narrower end whereby yielding fingers are formed at said narrower end, and a jacket of insulating material on the outer surface of said frustocone, also having longitudinal slits so as not to interfere with the yielding fingers.

3. A tool holder of the class described comprising a hollow frustocone having longitudinal slits at the narrower end whereby resilient fingers are formed in said frustocone at the narrower end, a lining of the same metal on the inside of said fingers near the extremities of same so as to facilitate the gripping of said fingers on the tool to be retained by same, and a jacket of insulated fiber on the outer surface of the frustocone, said fiber having longitudinal slits in register with the slits of the frustocone.

4. A tool holder of the class described in the shape of a hollow frustocone having lateral yielding fingers at the narrower end, a lining at the extremities of said fingers to increase the gripping action of same and a jacket about said cone to facilitate the handling of the holder.

JOHN BEN PERRY.
